GRINDING MACHINE

Harold L. Blood, Worcester, Mass., assignor to
 The Heald Machine Company, Worcester,
 Mass., a corporation of Massachusetts

Application December 21, 1936, Serial No. 116,879

19 Claims.

(Cl. 51—95)

The present invention relates to grinding machines and particularly to a machine in which the relative crossfeed movement between the grinding wheel and the workpiece may take place at a rapid rate until the grinding wheel engages the workpiece.

In grinding machines operating upon cylindrical or tapered surfaces the grinding wheel is normally given a crossfeed movement relative to the workpiece to bring the wheel and workpiece into grinding contact and thereafter to procure successively deeper and deeper cuts in the workpiece until the latter reaches the desired finished size. One of the principal objects of the present invention is to provide for reducing the rate of crossfeed movement when the wheel and workpiece come into contact independently of the unfinished workpiece size.

In internal grinding machines it is essential that the workpiece and the grinding wheel, at the beginning of the grinding operation, be positioned transversely of the machine relative to each other, so that the grinding wheel may enter the workpiece bore when either the grinding wheel or the workpiece is given an axial movement. After the wheel is positioned within the bore of the workpiece a relative transverse movement brings the grinding wheel and workpiece into grinding contact and for reducing the inoperative time of each grinding operation this transverse movement must take place as rapidly as possible. A further object of the present invention is accordingly to provide in internal grinding machines for a rapid crossfeed movement with a provision for reducing the rate of this movement immediately upon engagement between the wheel and workpiece and independently of the unfinished size of the workpiece.

In a copending application filed by Schmidt and Blood, Serial No. 68,291, filed March 11, 1936, is disclosed a structure by which the rate of crossfeed movement may be reduced upon engagement between the wheel and the workpiece, and this structure incorporates a grinding wheel which is a conductor of electricity and forms part of a circuit which is closed upon engagement between the wheel and the workpiece. This arrangement is entirely satisfactory in operation, but there are occasions when such an arrangement is not desirable, either by reason of the type of workpiece, the latter not being a conductor, or where the coolant forms such an insulation that a suitable electrical contact between the wheel and the workpiece cannot be effected. A further object of the present invention is to provide for the re-

duction in the rate of crossfeed movement without the necessity for forming either the wheel or the workpiece of a material which is an electrical conductor.

The present invention accordingly incorporates an alternative mechanism for accomplishing the same result as in the Schmidt and Blood application above referred to. In the present invention the rate of crossfeed movement is reduced in response to movement of the wheelhead relative to its support with this movement produced by the pressure between the grinding wheel and the work. The arrangement is such that a very slight amount of wheelhead movement is necessary for procuring the desired reduction in the rate of transverse movement and it will be understood that the workhead can be alternatively mounted for the movement necessary to obtain this reduction in the transverse movement.

Other and further objects and advantages of the invention will more fully appear from the following detailed description taken in connection with the accompanying drawings in which—

Fig. 1 is a front elevation of a machine embodying the invention.

Fig. 2 is a plan view of the machine of Fig. 1.

Fig. 3 is a vertical section substantially along the line 3—3 of Fig. 2.

Fig. 4 is a vertical section substantially along the line 4—4 of Fig. 3, with parts broken away to show the crossfeed mechanism more clearly.

Fig. 5 is an end view of the wheelhead and associated mechanism with parts broken away.

Fig. 6 is a fluid pressure diagram.

Fig. 7 is a wiring diagram.

Like reference characters refer to like parts in the different figures.

Referring first to Fig. 1, the machine has the usual reciprocating table 1 provided in an internal grinding machine; either the grinding wheel or the workpiece to be ground is carried on the table, the reciprocations of the latter operating in either case to produce a relative translatory movement between the wheel and the workpiece. In the construction shown the table supports and carries a workhead 2 and the wheelhead 3 is mounted on a bridge 4, Fig. 3, which spans the guideways 5 provided by the base 6 of the machine for the movements of the table. The grinding wheel 7 is carried on a spindle 8 journaled in the wheelhead and is suitably rotated at a high rate of speed by any well known mechanism, which in the present instance consists of a motor, not shown, in the base of the machine connected by a belt, to a pulley 9 on the spindle.

The workpiece *a*, Figs. 1 and 3, is mounted in a suitable work-supporting structure which may be in the form of a chuck *10* carried on a spindle *11* journaled in the work-head. The chuck is preferably driven at a relatively slow rate of speed from a motor *12* connected to the spindle *11* by a belt *13*. The clutch mechanism *14*, of any well known construction, provides for stopping the rotation of the chuck without interfering with the operation of the motor *12*, and this mechanism is under the control of a handle *15* easily accessible to the operator of the machine. The reciprocations of the table *1* to cause the desired relative traverse between the rotating grinding wheel and the work-supporting structure are imparted in any well known manner, as by the use of fluid pressure controlling and reversing mechanism, one type of which is described in the Blood and Burns Patent No. 2,011,705, dated August 20, 1935. It is sufficient to note for the purpose of the present application that reversal of the table is procured at each end of the normal working stroke by spaced reversing dogs *16* and *17* which are carried by blocks *18* and *19* adjustably mounted on the front of the table *1* and adapted alternately to engage and move a reversing lever *20*. The reversing lever is connected by suitable mechanism to a reversing valve *21*, Fig. 6. The reversing lever *20*, during the grinding operation, when the grinding wheel is in the bore of the workpiece, is so located as to be engaged alternately by the reversing dogs.

Referring now to Fig. 6, the pump *22*, driven by a motor *23*, directs fluid under pressure from a tank *24* through a pipe *25* to the casing *26* in which the reversing valve *21* is positioned. The casing *26* has an inlet port *27* to which the pipe *25* is connected and also has spaced outlet ports *28* and *29* connected by pipes *30* and *31* respectively to the left and right hand ends of a cylinder *32* mounted in the base of the machine. A piston *33* slideable in the cylinder has a piston rod *34* connected to a depending lug *35* on the table *1*. The reversing valve alternately directs fluid under pressure to the outlet ports *28* and *29* and at the same time connects the opposite outlet port to an exhaust port *36* suitably connected to the tank.

Referring now to Fig. 3, the crossfeed movement between the workpiece and the grinding wheel is obtained by transverse movement of the wheelhead *3* on the bridge *4*. Movement of the cross slide *37*, Fig. 3, on which the wheel-head is mounted, is effected by rotation of the crossfeed screw *38*, which is held against endwise movement by anti-friction bearings *39* on the rearward end thereof. The crossfeed screw engages an internally threaded portion *40* of the cross slide for effecting the transverse movement thereof. On the forward end of the cross feed screw *38* is mounted a gear *41* which meshes with a pinion *42* secured against turning movement on a shaft *43* journaled in a housing *44* for the cross feed mechanism. Also secured to the shaft *43* in spaced relation to the gear *41* is a ratchet wheel *45* engageable by spaced oppositely directed pawls *46* and *47*, Fig. 4, carried by an annular member *48* secured against turning movement on a sleeve *49* journaled on the shaft *43*. The sleeve *49* has an integral pinion *50* engageable by a rack *51* horizontally slideable in the casing *44*, said rack being held in engagement with the pinion by a bearing *52*. The rack *51* is shifted by a fluid pressure mechanism hereinafter described in detail, and

procures through the pawl and ratchet arrangement a rotation of the shaft *43*, and accordingly a rotation of the crossfeed screw. Manual rotation of the crossfeed screw is by a hand wheel *43*.

The pawl and ratchet arrangement is fully described in the Guild Patent No. 1,971,138, dated August 21, 1934. It is sufficient to note for the purpose of the present application that this double pawl arrangement permits, during the return of the cross slide to original position, in readiness for a subsequent grinding operation, a compensation for the reduction in size of the grinding wheel as a result of wear, and the dressing operation performed thereon during the preceding grinding operation. With reference again to Figs. 3 and 4, it will be noted that both of the pawls are normally held in operative engagement with the ratchet by a spring *53*, and that the pawl *47* is operative during the crossfeed movement and the pawl *46* is operative during the retraction of the crossfeed movement, the latter involving a counterclockwise rotation of the member *48*. The pawl *46* is rendered inoperative during a part of the movement of the annular member *48* in the counterclockwise direction so that the cross slide is retracted a slightly shorter distance than it is moved forward during the crossfeed movement.

To effect this compensatory movement the shaft *43* has journaled thereon an arm *54* having a gear segment *55* on the outer end thereof. The gear segment engages with a pinion *56* on a shaft *57* journaled in the front wall of the housing *44* and the outer end of the shaft *57* has a knurled knob *58* by which said shaft is turned for shifting the position of the arm *54*. Integral with the arm *54* is a cam *59* in a position for engagement with a pin *60* on the pawl *46* just before the termination of the crossfeed movement. Thus, during the first part of the retraction of the crossfeed movement the pawl *46* is inoperative and rotation of the annular member *48* procures no corresponding movement of the ratchet wheel until the pawl *46* is released by the cam *59*. During the remainder of the counterclockwise movement of the member *48* the retraction of the crossfeed movement takes place.

Referring now to Figs. 4 and 6, the rack *51* is carried on the end of a piston rod *61* extending from a piston *62* slideable in a horizontally positioned cylinder *63* mounted on the front of the bridge. Fluid under pressure is directed alternately to opposite ends of the cylinder for procuring the crossfeed movement and the retraction thereof. As shown in Fig. 6, fluid under pressure from the pipe *25* passes through a pipe *64* to the inlet port *65* of a reversing valve casing *66* for a reversing valve *67* for the crossfeed mechanism. An outlet port *68* in the casing *66* is connected by a conduit *69* to the left hand end of the cylinder *63* and a second outlet port *70* is connected by a conduit *71* and suitable valve mechanisms hereinafter described, to the right hand end of the cylinder *63*. An exhaust port *72* for the reversing valve casing *66* is suitably connected to the tank *24* and provides for exhaust of fluid from the cylinder.

The structure above described is similar to structure already disclosed and claimed in prior patents and pending applications and is not, of itself, the present invention. The latter involves, in connection with the above or similar grinding machine elements, the attainment of the objects and novel features above outlined. In accordance

with the present invention the movement of the wheelhead resulting from engagement between the grinding wheel and workpiece during the crossfeed movement, is used to procure a change 5 in the grinding operation. This change, in the structure described for one embodiment of the invention, is a reduction in the rate of crossfeed movement, although it will be apparent that other changes in the grinding operation may be 10 controlled or procured by similar mechanism.

With reference now to Figs. 5 and 6, the wheelhead 3 is supported for rocking movement on the cross-slide 37 by means of flat springs 73 attached at their opposite ends, as by bolts 74, to a 15 slide 75 secured in the cross-slide. The springs 73 are centrally connected by suitable bolts 76 to the wheelhead and the springs are shaped to provide for a small amount of oscillatory movement 20 of the wheelhead on the slide 75, the wheelhead 25 rocking about lugs 77 on the slide 75 in line with the bolts 76.

Referring again to Fig. 5, the cross-slide 37 has mounted thereon forwardly of the wheelhead, a 30 housing 78 on which is mounted, for rocking movement, a lever 79. The support for this lever preferably comprises one or more flat springs 80 connected at one end to the housing 78 and at the opposite end to one end of the lever 79. The lever 79 is connected between its ends thereof to 35 the wheelhead 3 by similar flat springs 81. Rocking movement of the wheelhead 3 in the direction of the arrow 82, resulting from engagement between the grinding wheel and the workpiece will procure a clockwise swinging movement of the 40 lever 79 by which the change in the grinding operation is effected. The swinging movement of the wheelhead is limited by an adjustable bolt 83 on the housing 78.

The lower end of the lever 79 has an electrical 45 contact 84 (shown in Fig. 7 as attached directly to the wheelhead) and this contact engages with a stationary contact 85 on the housing 78 when the grinding wheel engages the workpiece. Referring now to the wiring diagram of Fig. 7, a 50 source of power is represented by the transformer 86. One side of the secondary winding 87 of the transformer is connected by a lead 88 to the contact 84 on the lever 79 (on the wheelhead, Fig. 6). The other side of the secondary winding 87 is connected by a lead 89 to a contact 90 of a switch 91, the other contact 92 of the switch being connected by a lead 93 to one terminal of a solenoid 94. The other terminal of the solenoid is connected by a lead 95 to the contact 85. The armature 96 of the solenoid 94 is connected by a link 97 to the lever 79 and energization of the solenoid by engagement between contacts 84 and 85 thus urges the armature to the left to hold the contacts in engagement and to hold the wheelhead against 60 the adjustable bolt 83.

Integral with the armature 96 of the solenoid 94 is a valve 98 in a casing 99 forming an integral part of the housing 78 and this valve is shifted to the left when the solenoid is energized 65 for materially reducing the rate of crossfeed movement. With reference to Fig. 6, the casing 99 has a part 100 connected by a conduit 101 to the conduit 71 and a second port 102 connected by a conduit 103 to the right hand end of the cylinder 63. A reduced portion 104 of the valve 70 normally provides fluid connection between the ports 100 and 102 so that the crossfeed movement occurs at a maximum rate determined by a main 75 throttle valve 105 in the conduit 71. When the solenoid 94 is energized, the fluid connection

through the valve 98 is cut off and fluid then enters the cylinder 63 at a reduced rate through a valve 106.

Again referring to Fig. 6, the valve 106 is positioned in a casing 107 in a block 108 mounted on the front of the bridge directly above the cylinder 63, as shown in Fig. 4. The conduit 71 is connected to a channel 109 in the block 108 which intersects spaced bores in which a rough feed valve 110 and a fine feed valve 111 are respectively positioned. The casing 107 has a port 112 communicating with the end of the valve 110 and a spaced port 113 communicating with the valve 111. With the valve 106 in the normal position, which is the position at the beginning of the 15 grinding operation, a reduced portion 114 of the valve 106 provides a connection between the port 112 and a channel 115 in the casing 107, block 108 and cylinder 63, this channel communicating with the right hand end of the cylinder 63. The channel 115 is represented in part, in Fig. 6, by a conduit 115', for the sake of clarity. Thus when the fluid connection through the valve 98 is cut off, as above stated, the crossfeed movement occurs at a relatively slow rate, as determined by the 25 setting of the rough feed valve 110.

Subsequent to the shifting of the valve 98, and during the grinding operation, the valve 106 is shifted to the right, for reducing the rate of crossfeed movement still more. When this occurs the connection from the port 112 to the channel 115 is cut off and a reduced portion 116 of the valve 106 provides a connection between the port 113 and a branch channel 117 communicating with the channel 115. During the remainder of the grinding operation the crossfeed movement occurs at an extremely slow rate determined by the setting of the fine feed valve 111. The shifting of the valve 106 is procured by a cam 118, Fig. 4, on the member 48, this 30 cam, during the grinding operation, engaging with a roller 119 on the end of a plunger 120 in line with the valve 106. Movement of the plunger to the left beyond the position of Fig. 4 is limited by a cap 121 and the valve 106 is held 35 against the plunger by a coil spring 122 in a recess 123 at the right hand end of the valve.

In the operation of the machine, the workpiece is loaded while the table is in the position shown, and the workpiece and grinding wheel 50 are then brought into operative position by shifting a lever 124 on the front of the machine, this lever being suitably connected to the table reversing valve 21. As the table approaches its operative position, with the grinding wheel located in the bore of the workpiece, the valve 67 is suitably shifted from the position shown into its opposite position for directing fluid through the valve 98 to the crossfeed cylinder 63. The valve 67 may be automatically shifted, as for example in response to the table movement.

The crossfeed movement, being procured by the shifting of the valve 67, occurs at a rapid rate as determined by the throttle valve 105 until the grinding wheel is moved laterally from 65 the position of Fig. 3 into engagement with the workpiece. When engagement between the workpiece and grinding wheel occurs, the wheelhead 3 is rocked to establish a circuit through the solenoid 94 to hold the wheelhead against further 70 rocking movement and to reduce materially the rate of crossfeed movement by cutting off the flow of fluid through the valve 98.

The grinding operation then continues at the rate determined by the rough feed valve 110 and 75

subsequently at a rate determined by the fine feed valve 111, until the workpiece reaches a predetermined size. The grinding operation may be under the control of any suitable mechanism, as for example, the mechanism disclosed in the above cited Blood and Burns Patent No. 2,011,705. In any event the grinding operation is terminated by an extended movement of the table to the left into the rest position shown.

10 During the extended movement of the table the crossfeed control valve 61 is shifted for retracting the crossfeed movement, and as the table reaches rest position a cam 125 on the table opens the switch 91 to deenergize the solenoid 94. When this occurs the wheelhead 3 returns to the vertical position of Fig. 5, by the resiliency of springs 73, and the valve 98 is thus restored to the position of this figure for exhaust of the fluid from the cylinder 63 through this 20 valve.

From the foregoing it will be apparent that the present invention provides a mechanism by which a change in the grinding operation is effected upon engagement between the grinding 25 wheel and the workpiece. By the arrangement shown the change involves a reduction in the rate of crossfeed movement procured by a movement of the wheelhead relative to the machine. By this arrangement the wheel may be moved laterally of the workpiece at a maximum rate until it comes in contact with the workpiece.

I claim,

1. In a grinding machine, a spindle having a wheel thereon, a member in which said spindle 35 is journalled, a work-supporting member having a workpiece mounted therein, means for procuring a relative movement between said members, means for supporting one of said members for movement relative to the supporting structure upon engagement between the wheel and the workpiece, and means responsive to said movement relative to the supporting structure for procuring a change in the machine operation.

2. In a grinding machine, a spindle having a 45 wheel thereon, a member in which said spindle is journalled, a work-supporting member having a workpiece mounted therein, means for procuring a relative movement between said members, means for supporting one of said members for movement relative to the supporting structure upon engagement between the wheel and the workpiece, and means responsive to said movement relative to the supporting structure for procuring a change in the rate of relative 50 movement between the members.

3. In a grinding machine, a spindle having a wheel thereon, a member in which said spindle is journalled, a work-supporting member having a workpiece mounted therein, means for procuring a relative movement between said members, means for supporting one of said members for movement relative to the supporting structure upon engagement between the wheel and the workpiece, and means responsive to said 55 movement relative to the supporting structure for procuring a reduction in the rate of relative movement between the members.

4. In a grinding machine, a wheel supporting member having a wheel thereon, a work-supporting member having a workpiece mounted therein, means for procuring a relative movement between said members, means for supporting one of said members for movement relative to the supporting structure upon engagement between the 70 wheel and the workpiece, and means respon-

sive to said movement relative to the supporting structure for procuring a change in the machine operation, said last means also providing for locking the movable member against further movement relative to the supporting structure. 5

5. In a grinding machine, a wheel supporting member having a wheel thereon, a work-supporting member having a workpiece mounted therein, means for procuring a relative movement between said members, means for supporting one of said members for movement relative to the supporting structure in response to engagement between the wheel and the workpiece, and means responsive to said movement relative to the supporting structure for procuring a reduction in the rate of relative movement between the members, said last means also providing for locking the movable member against further movement relative to the supporting structure during the remainder of the grinding operation. 20

6. In a grinding machine, a spindle having a wheel thereon, a member in which said spindle is journalled, a work-supporting member having a workpiece mounted therein, means for procuring a relative movement between said members, 25 means for supporting one of said members for movement relative to the supporting structure therefor upon engagement between the wheel and the workpiece during the said relative movement, and hydraulically actuated means movable in response to said movement relative to the supporting structure for procuring a change in the machine operation.

7. In a grinding machine, a spindle having a wheel thereon, a member in which said spindle is journalled, a work-supporting member having a workpiece mounted therein, means for procuring a relative movement between said members, means for supporting one of said members for movement relative to the supporting structure 40 therefor upon engagement between the wheel and workpiece during said relative movement, a valve means for reducing the rate of relative movement between the members, and electrically actuated means energized in response to movement 45 of the movable member relative to the supporting structure for shifting said valve.

8. In a grinding machine, a wheel supporting member having a wheel thereon, a work-supporting member having a workpiece mounted therein, means for procuring a relative movement between said members, means for supporting one of said members for movement relative to the supporting structure therefor upon engagement between the wheel and workpiece during said relative 55 movement, hydraulically actuated means for procuring a change in the machine operation, and means responsive to the movement of the movable member relative to the supporting structure for locking the movable member against further 60 movement relative to the supporting structure, and for actuating said hydraulically actuated means.

9. In a grinding machine, a wheel supporting member having a wheel thereon, a work-supporting member having a workpiece mounted therein, means for procuring a relative movement between said members, means for supporting one of said members for movement relative to the supporting structure therefor upon engagement between the 70 wheel and workpiece during said relative movement, hydraulically actuated means for procuring a change in the machine operation, and electrically actuated means responsive to said movement of one of said members relative to the 75

- supporting structure for locking said last mentioned member against further movement relative to the supporting structure and for energizing said hydraulically actuated means.
5. In a grinding machine, a wheel supporting member having a wheel thereon, a work-supporting member having a workpiece mounted therein, a cross slide on which one of said members is mounted for a crossfeed movement between said members, means for supporting one of said members for a slight rocking movement relative to the supporting structure when the grinding wheel engages the workpiece in the work-supporting member, and means responsive to said rocking movement for changing the rate of crossfeed movement.
10. In a grinding machine, a wheel supporting member having a wheel thereon, a work-supporting member having a workpiece mounted therein, a cross slide on which one of said members is mounted for a crossfeed movement between said members, means for supporting one of said members for a slight rocking movement relative to the supporting structure when the grinding wheel engages the workpiece in the work-supporting member, and means responsive to said rocking movement for changing the rate of crossfeed movement.
15. In a grinding machine, a wheel supporting member having a wheel thereon, a work-supporting member, means for procuring a feeding movement between said members, means for supporting one of said members for a rocking movement relative to the supporting structure when the grinding wheel engages a workpiece in the work-supporting member, and means responsive to said rocking movement for procuring a change in the rate of feeding movement.
20. In a grinding machine, a wheel supporting member having a wheel thereon, a work-supporting member, means for procuring a feeding movement between said members, means for supporting one of said members for a rocking movement relative to the supporting structure when the grinding wheel engages a workpiece in the work-supporting member, and means responsive to said rocking movement for procuring a change in the rate of feeding movement.
25. In a grinding machine, a wheel supporting member having a wheel thereon, a work-supporting member, fluid pressure actuated means for moving the cross slide, a valve for controlling the fluid pressure actuated means and electrically actuated means responsive to said rocking movement for shifting said valve.
30. In a grinding machine, a wheel supporting member having a wheel thereon, a work-supporting member having a workpiece mounted therein, a cross slide on which one of said members is mounted for a crossfeed movement between said members, means for supporting one of said members for a slight rocking movement relative to the supporting structure when the grinding wheel engages the workpiece in the work-supporting member, means responsive to said rocking movement for changing the rate of crossfeed movement and for locking the member against further rocking movement during the remainder of the grinding operation.
35. In a grinding machine, a wheel supporting member having a wheel thereon, a work-supporting member having a workpiece mounted therein, a cross slide on which one of said members is mounted for a crossfeed movement between said members, means for supporting one of said members for a slight rocking movement relative to the supporting structure when the grinding wheel engages the workpiece in the work-supporting member, means responsive to said rocking movement for procuring a change in the rate of feeding movement and for locking the rockable member against rocking movement in response to said rocking movement.
40. In a grinding machine, a wheel supporting member having a wheel thereon, a work-supporting member, hydraulically actuated means for procuring a relative movement between said members, means for supporting one of said members for a rocking movement relative to the supporting structure when the grinding wheel engages a workpiece in the work-supporting member, a valve for controlling said hydraulically actuated means and electrically actuated means responsive to the rocking movement for shifting said valve.
45. In a grinding machine, a wheel supporting member having a wheel thereon, a work-supporting member, hydraulically actuated means for procuring a relative movement between said members, means for supporting one of said members for a rocking movement relative to the supporting structure when the grinding wheel engages a workpiece in the work-supporting member, a valve for controlling said hydraulically actuated means, and means responsive to the rocking movement for locking the rockable member against further rocking movement and for shifting said valve.
50. In a grinding machine, a wheel supporting member having a wheel thereon, a work-supporting member, hydraulically actuated means for procuring a relative movement between said members, means for supporting one of said members for a rocking movement relative to the supporting structure when the grinding wheel engages a workpiece in the work-supporting member, a valve for controlling said hydraulically actuated means, and means responsive to the rocking movement for locking the rockable member against further rocking movement and for shifting said valve.
55. In a grinding machine, a wheel supporting member having a wheel thereon, a work-supporting member, hydraulically actuated means for procuring a relative movement between said members, means for supporting one of said members for a rocking movement relative to the supporting structure when the grinding wheel engages a workpiece in the work-supporting member, a valve for controlling said hydraulically actuated means, and means responsive to the rocking movement for locking the rockable member against further rocking movement and for shifting said valve.
60. In a grinding machine, a wheel supporting member having a wheel thereon, a work-supporting member, means for procuring a feeding movement between said members, means for supporting one of said members for a rocking movement relative to the supporting structure when the grinding wheel engages a workpiece in the work-supporting member, a valve for controlling said hydraulically actuated means, and means responsive to the rocking movement for locking the rockable member against further rocking movement and for shifting said valve.

HAROLD L. BLOOD.
